US0D1064543S

(12) **United States Design Patent** (10) **Patent No.:** **US D1,064,543 S**
(45) **Date of Patent:** **** Mar. 4, 2025**

(54) **FOOTWEAR SOLE**

(71) Applicant: **Saucony, Inc.**, Waltham, MA (US)

(72) Inventors: **Christopher J. Mahoney**, Concord, MA (US); **Luca B. Ciccone**, Leominster, MA (US)

(73) Assignee: **Saucony, Inc.**, Waltham, MA (US)

(**) Term: **15 Years**

(21) Appl. No.: **29/883,179**

(22) Filed: **Jan. 25, 2023**

(51) LOC (15) Cl. **02-04**

(52) U.S. Cl.

(57) **CLAIM**

The ornamental design for a footwear sole as shown and described.

DESCRIPTION

FIG. 1 is a perspective view of the footwear sole embodying the new design;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

The broken lines immediately adjacent to the solid line portions of the design form the boundary of the design, with the broken lines forming no part of the claimed design.

1 Claim, 7 Drawing Sheets
